UNITED STATES PATENT OFFICE

WALTER H. SCHRAMM, OF PITTSBURGH, PENNSYLVANIA, ASSIGNOR TO WESTINGHOUSE ELECTRIC & MANUFACTURING COMPANY, A CORPORATION OF PENNSYLVANIA

INSULATOR

Application filed April 2, 1927. Serial No. 180,442.

My invention relates to insulators and particularly to insulators subject to cantilever loads, such as those for supporting bus-bars, switches and the like.

5 One object of my invention is to provide a device of the above-indicated character that shall so convert cantilever load forces into compression forces as to provide a more effective insulator than those heretofore employed and one that is less subject to damage.

10 Another object of my invention is to provide a bus-bar or similar insulator, subject to cantilever load, that shall utilize the advantages of fibrous insulating material 15 under tension and refractory insulating material under compression.

Another object of my invention is to provide an insulator that shall so embody a relatively-short and small-diameter fibrous 20 strain rod and a longer refractory insulating tube of considerably greater diameter as to facilitate the conversion of cantilever load forces into compression forces, to provide a stable base for the insulator and to utilize 25 the surface-creepage distance of the refractory tube to maximum advantage.

Another object of my invention is to provide an insulator that shall embody a tubular insulating member of relatively great diameter or base area for co-operation with a main supporting structure, and a single means for holding a conductor, converting cantilever load forces into compression forces and mounting the insulator.

35 Another object of my invention is to provide an insulator that shall comprise parts of such relation and simple form as to greatly facilitate the manufacture and assembly thereof.

40 A further object of my invention is to provide an insulator that shall be compact and durable in construction, economical to manufacture and effective in its operation.

In insulators for supporting bus-bars and 45 other conductors in such position and relation as to subject the same to cantilever loads, damage, caused by bending tendency of the insulators, frequently occurs and, in insulators embodying refractory or similar 50 hard brittle material, this damage usually

occasions break down of the insulator, with the resulting economical loss in labor and material, as well as the interruption of service.

Insulators of the character specified above 55 have also, usually, embodied terminal members or end caps which shorten the surface-creepage distance thereof. Accordingly, in practicing my invention, I provide a refractory insulating member that is so worked in compression, a fibrous insulating member 60 that so shares the load and assists in converting the cantilever forces into compression forces in the refractory member and other features that are so combined and related to the refractory and fibrous members 65 as to overcome the objectionable features of prior insulators and to attain the objects set forth above.

The single figure of the accompanying 70 drawing is a side view, partially in section and partially in elevation, of an insulator constructed in accordance with my invention.

The device comprises, in general, an outer 75 tubular shell or protective member 2, a strain insulator therein comprising an insulating rod or member 3 and metal end or terminal structures 4; end closure members 6 for the shell 2, cushioning and sealing 80 means 7 between the shell 2 and the end-closure 6, nuts 9 and lock washers 10 for holding the end-closure members 6 in position and a body 12 of insulating filler material in the shell 6 about the strain insulator 85 3 and portions of the terminals 4 thereof.

The shell 2, preferably of refractory insulating material, such as porcelain or glass, is formed as a cylindrical tube having ends that are preferably flat or substantially normal to the longitudinal axis of the tube 90 corrugated outer surfaces 14 and inner surfaces 15 that are sloped to render the tube slightly thicker at its mid portion than at its ends.

The rod 3, of fibrous insulating material, such as wood, impregnated paper or cloth, molded composition or other suitable material, is preferably provided with substantially frusto-conical ends 17 and an annular 100

corrugated intermediate portion 18 that is thicker at its central section than at the lesser bases of the frusto-conical ends 17. The lateral extreme end surfaces of the member 3 are offset from the corresponding end surfaces of the shell 2.

Each of the terminal structures 4 preferably comprises a portion 20, initially of substantially straight-sided cup-shape, that is swaged in position over one of the frusto-conical ends 17 and a screw-threaded shank portion 21 on which one of the nuts 9 is mounted.

Each end-closure member 6 is preferably constructed of yieldable or resilient sheet material, such as sheet steel having a suitable coating thereon, to be of substantially discoidal character having substantially parallel-plane offset inner and outer portions 23 and 24 that are disposed over, and co-operate with, the ends of the strain insulator 3 and the shell 2, respectively.

This construction provides a space, between the end of the strain insulator 3 and the end of the shell 2, for the nut 9 and the lock washer 10 or other suitable holding means co-operating between the shank 21 and the end-closure member 6, whereby space is conserved and the insulator is provided with suitable end areas for stable mounting of the insulator and stable mounting of a bus-bar or other structure on the insulator.

The end disks or plates 6 are also so biased inwardly on the insulator 3 against the gaskets 7 and shell 2 by the nuts 9 as to place the shell 2 in compression and to effect a strong seal against the escape of the filler material 12.

In the above-described structure, the strain insulator or rod 3, together with its end terminal members 3, constitute a single means for holding a bus-bar or other conductor, for assisting in converting bending forces into compression forces in the shell 2 and for holding the entire insulator to a main stationary supporting structure (not shown) at a single position between the insulator and the main supporting structure. This position is along, and closely adjacent to, the base-end shank 21, in contradistinction to prior-art structures having a plurality of bolts distributed about the perimeter of the insulators at the base ends thereof.

Further, since the members 6 are of discoidal form and do not extend along the outer surface of the shell 2, as in prior practice, the full insulating value of the surface 14 is obtained, giving greater effective length to the insulator for the same amount of material.

In operation, with one end of the insulator fixed to the main supporting structure, cantilever load at the other end thereof tends

to bend the strain insulator near the main support. This tendency biases the outer plate 6 against the shell 2, whereby the latter, in addition to the compression effected therein by the plates 6, as above described, is subjected to load compression. The shell 2 is, therefore, relatively free of any forces except compression forces and is thereby operated under its best condition.

By my invention, an insulator is provided that embodies parts of simple manufacture and easy assembly which are operated under advantageous conditions and are protected against damage. The device is also adapted for the ready mounting thereof and the reception thereon of the conductor which it is to support, is rugged and durable, is effective in operation, and is, in general, an improvement over similar devices heretofore employed.

While I have shown and described a particular form of my invention, changes may be effected therein without departing from the spirit and scope thereof, as set forth in the appended claims.

I claim as my invention:

1. An insulator subject to cantilever load comprising a tubular insulating shell of relatively large diameter and short length, an insulating strain rod therein of small diameter compared to the diameter of the shell and having ends inwardly offset from the ends of the shell, means for closing the ends of the shell and converting cantilever load forces of the rod into compression forces in the shell including end plates having perimetral portions co-operating with the ends of the shell and inwardly-offset apertured portions co-operating with the ends of the rod, metal terminal members at the ends of the rod having portions projecting through the apertured portions of the plates, means for securing and sealing the plates in position, and an insulating filler material surrounding the rod in the shell.

2. An insulator comprising a tubular insulating member, a strain insulator disposed therein with an end inwardly offset from an end of the tubular member and an end-closure member of discoidal sheet-material character having its outer perimeter co-operating with the end of the tubular member and a depressed central portion co-operating with the end of the strain insulator.

3. An insulator comprising a tubular insulating member, a strain insulator disposed therein with an end inwardly offset from an end of the tubular member and an end-closure member of discoidal resilient sheet-material character having its outer perimeter over the end of the tubular member and its central portion flexed inwardly and fixed to the strain insulator.

4. An insulator comprising a tubular insulating member, a strain insulator disposed

- therein with an end inwardly offset from an end of the tubular member, an end closure member of discoidal sheet-material character having substantially parallel-plane offset portions over said ends and means in the space provided by the offset portions of the disk for securing the disk to the strain insulator. 5. An insulator comprising a tubular insulating member, a strain insulator disposed therein with an end inwardly offset from an end of the tubular member and a terminal shank projecting outwardly beyond said tubular end, an end closure member of discoidal sheet-material character having substantially parallel-plane offset portions over said ends and means in the space provided by the offset portions of the disk co-operating between the shank and the disk 10 for holding the disk in position. 6. An insulator comprising a tubular insulating member, a strain insulator disposed therein with an end inwardly offset from an end of the tubular member and a terminal shank projecting outwardly beyond said tubular end, an end closure member of discoidal sheet-material character having substantially parallel-plane offset portions over said ends, a yieldable gasket 15 between the discoidal and tubular members and locking-nut means on the shank in the space provided by said offset portions of the disk for holding the disk in position. 7. An insulator comprising a refractory insulating tube having sloping inner surfaces and walls of longitudinally-varying thickness, a fibrous strain insulator therein having its ends inwardly offset from the ends of the tube, metal terminal members 20 having portions secured to the ends of the strain insulator and shanks projecting beyond the ends of the tube, discoidal metal members having offset substantially parallel-plane portions over the ends of the tube 25 and strain insulator, means within the outer planes of the disk for holding the disks in position and an insulating filler medium surrounding the strain insulator in the tube. 8. An insulator comprising a refractory insulating tube having flat ends, a fibrous strain insulator therein having its ends inwardly offset from the ends of the tube, metal terminal members having cup-portions secured in position over the strain-insulator ends and shanks projecting beyond the ends of the tubular member, sheet-metal disks having parallel-plane offset portions over the ends of the tube and strain insulator, means in the spaces provided by said offset disk portions co-operating between the disks and the shanks for holding the disks in position and a body of insulating material filling the remaining space in the tube. 9. An insulator comprising a refractory insulating tube having flat ends and corrugated outer side surfaces, a wood strain insulator disposed therein having corrugated sides and frusto-conical ends inwardly offset from the ends of the tube, metal terminal members having cup portions swaged in position over said frusto-conical ends and screw-threaded shanks projecting beyond the ends of the tubular member, sheet-metal disks having parallel-plane offset portions over the ends of the tube and strain insulator, lock washers and nuts in said shanks in the spaces provided by said offset disk portions, yieldable gaskets between the tubular member and the disks and a body of insulating material filling the remaining space in the tubular member. 10. An insulator subject to cantilever loads comprising a refractory insulating tube of relatively large diameter and short length having flat ends and corrugated outer side surfaces, a fibrous insulating strain rod therein of small diameter compared to the diameter of the tube and having substantially frusto-conical ends inwardly offset from the ends of the tube, metal terminal members having cup portions swaged in position over said frusto-conical ends and screw-threaded shanks projecting beyond the ends of the tube, means for closing the ends of the tube and converting cantilever load forces of the rod into compression forces in the tube including apertured sheet-metal disks having substantially parallel-plane offset portions over the ends of the tube and the rod, yieldable gaskets between the disks and the tube, locking nut means on the shanks for holding the disks and an insulating filler material in the tube. In testimony whereof I have hereunto subscribed my name this 30th day of March, 1927.
- WALTER H. SCHRAMM.
